UNITED STATES PATENT OFFICE.

OSCAR A. ROSS, OF ROCHESTER, NEW YORK, ASSIGNOR TO GENERAL RAILWAY SIGNAL COMPANY, OF GATES, NEW YORK, A CORPORATION OF NEW YORK.

AUTOMATIC TRAIN-CONTROL SYSTEM.

1,263,603.

Specification of Letters Patent. Patented Apr. 23, 1918.

Application filed June 26, 1915. Serial No. 36,535.

To all whom it may concern:

Be it known that I, OSCAR A. Ross, a citizen of the United States, and a resident of the city of Rochester, in the county of Monroe and State of New York, have invented 5 a new and useful Automatic Train-Control System, of which the following is a specification.

This invention relates to automatic train 10 control systems, and more particularly to such systems in which the movement of the train is controlled, in some appropriate manner, by an electrically operated device located on the train, as a control relay, the 15 control of said device being accomplished by suitable ramps or other devices arranged along the trackway and adapted to coöperate with shoes or other devices carried by the train.

20 One of the principal objects of the invention is to construct and arrange the parts of a train control system of the character specified so that a number of units, such as two or more locomotives or motor cars, may 25 be included in the same train without affecting the operation of the train control system or impairing its efficiency.

A further object of the invention is to 30 devise a simple and reliable train control apparatus and ramps, circuits and electrical connections therefor arranged along the trackway which will operate to properly control the control relay or other controlling device on each locomotive or motor car included in a train, regardless of the number 35 of locomotives or motor cars, or their position in the train, or of the length of the blocks or of the train.

Other objects and advantages will appear 40 as the description of the invention progresses, and the novel features of the invention will be particularly pointed out in the appended claims.

Generally stated, the invention consists 45 in providing a short control section at the entrance to each block section of the trackway over which the train passes to which is connected and by which is controlled suitable electrical appliances so that the condition of the ramp or control device adjacent 50 to each control section will be maintained

the same while the train is passing that control section.

The invention further consists in the parts and in the arrangements and combinations of parts, more fully set forth herein-after.

In describing the invention in detail, reference is had to the accompanying drawing, 60 wherein I have illustrated a preferred physical embodiment of my invention, and wherein like characters of reference designate corresponding parts throughout the several views, and in which:

Figure 1 is a diagrammatic illustration of 65 a railway train and a track for said train, and shows the parts associated with the train and with the track and the circuits and electrical connections between said parts which embody the invention, the parts in 70 said figure being shown in their normal positions and in the condition existing when a train approaches one of the ramps located along the track; and Fig. 2 is a diagrammatic illustration similar to Fig. 1, and 75 shows a slightly modified arrangement of the circuits.

Referring to the accompanying drawings, one track rail 1 of the railway track is electrically continuous, the separate rails thereof being suitably bonded together; and the other track rail 2 of said railway track is divided into electrically distinct sections A, B, C, D and E in any suitable way, as by insulating joints 3. The sections A, C and 80 E may be of any length desired to obtain the required spacing of the trains, and for convenience in description will be herein-after termed block sections. The sections B and D are comparatively short and may 85 be as short as desired, providing that they are longer than the distance between any two successive pair of wheels. In other words, the sections B and D, which will be herein-after termed control sections, are 90 long enough so that as the train passes over them at least one pair of wheels of said train will at all times be on said control section. Although only two control sections B and D, the intermediate block section C 100 and the adjacent ends of the two block sections A and E, are shown in the drawings,

it is to be understood that the same alternate arrangement of control sections and block sections is carried out throughout the desired length of the track, a control section 5 being located at the entrance to each block section, as illustrated, the direction of normal traffic being indicated by the arrow X.

Across the two track rails 1 and 2 at one end of each block section A, C and E is 10 connected a source of electric current, as a battery 4; and at the other end of each block section a track relay 7 is connected across the track rails 1 and 2 by conductors 5 and 6. The parts and circuits are the same for 15 the control sections B and D, and the conductors and parts of the control section D are given the same reference character as the corresponding parts and conductors of the control section B with a distinctive 20 component "1" added thereto. These track relays 7, together with the track rails 1 and 2 and the battery 4, constitute the well known normally closed track circuit, as will be readily understood by those skilled in the 25 art of railway signaling. The track relay for each block section is normally energized, that is, when no train occupies that block section, and their armatures will be normally held in their upper position, as shown 30 in the drawing.

Associated with each control section is a relay 8, hereinafter termed a ramp relay, which is connected by a conductor 9 to the track rail 2 and by conductors 10 and 11 to a 35 local source of current, such as a battery 12, which in turn is connected by a conductor 13 to the track rail 1. Adjacent to each control section B and D is a contact rail or ramp R, which is supported in any suitable 40 way on the ties of the railway track, but is insulated from said ties and from the track rails.

The conductors and electrical connections between the different operative parts of the 45 control system along the trackway will not be described in detail since these connections and the different operating circuits will be fully set forth hereinafter in the description of the operation.

50 The apparatus on the vehicle for controlling the movement thereof may be of any suitable construction, but is illustrated as constructed and arranged so that it will not be affected if a difference of potential exists 55 between the ramp R and the track rail 1, but will be set into operation to control the movement of the train in some appropriate manner in case such difference of potential does not exist. The railway train is shown 60 diagrammatically as comprising two pairs of wheels 14-14 and 16-16 connected by axles 15 and 17 respectively which represent the wheels and axles of separate cars or locomotives constituting a train. The axles 65 15 and 17 are illustrated as connected by a

bar 18 which represents the frames of the cars or locomotives constituting the train.

A bracket 19 of insulating material is suitably supported on the train, being shown as mounted on the rear axle 17; and supported 70 on the bracket 19 is a vertically movable shoe or plunger 20, which is pressed downwardly by a spring 21. The shoe 20 is arranged to coöperate with the ramps R arranged along the trackway and is designed to make electrical contact with said ramps and also to be raised so as to interrupt a normally closed circuit on the train. To accomplish this purpose, the shoe 20 may be provided with a button 24 of insulating material arranged 75 to lift a contact spring 22 out of contact with a contact member 23, said button 24 also serving to limit downward movement of the shoe 20. The contact spring 22 and the contact member 23 are suitably secured to the 80 bracket 19, which being of insulating material, serves to insulate said contact spring and said contact member from each other and from the frame of the vehicle.

The contact spring 22 and the contact 90 member 23 control a normally closed circuit for maintaining a control relay 25 energized. This control relay 25 has two armatures 27 and 28, one armature 27 being interposed in the local normally closed circuit for said relay 25, and the other armature 28 controlling a local normally closed circuit for a device K by means of which the movement of the train is controlled. This device K may be of any suitable construction, but is illustrated as set into operation when deenergized and restored to its normal position when energized. This device K may be used to apply the brakes on the train instantaneously when it is operated or after a certain 105 interval, which may be fixed or variable according to the speed of the train and the distance it has traveled after said device K was set into operation. Various devices well known in the art will satisfy the requirements of the device K and a detail description of said device will not be given here.

Having described generally the structure and arrangement of the various parts constituting a system for automatically controlling railway trains which embodies the invention, the operation of said system will be described for different cases in which certain conditions, such as may occur in practice, are assumed to exist along the trackway.

Referring to Fig. 1, for the first condition to be considered, assume that the train under consideration is in the block section A, as shown in said figure, and is about to enter the control section B; that the train has 125 found the trackway unobstructed and is running without being under the control of the device K; and that there is no train either in the block section C, the control section D, or the block section E. Since the 130

block sections C and E are not occupied, the track relays 7 and 7¹ therefor will be energized by current supplied from the batteries 4, as will be clearly understood by those skilled in the art; and since said track relays are energized, their armatures 32, 33 and 32¹, 33¹ will be in their raised position, as shown. The ramp relay 8 for the ramp R at the entrance to the control section B is deenergized and its armatures 30 and 31 are in their lower position, as shown. A difference of potential exists between the ramp R and the track rail 1 according to the partial circuit as follows: from the ramp R, conductor 34, armature 30 of the ramp relay 8 in its lower position, conductor 35, armature 32 of the track relay 7 in its upper position, conductors 36, 37 and 11, battery 12 and conductor 13 to the track rail 1.

It is noted that this first partial circuit for maintaining a difference of potential between the ramp R and the track rail 1 will be interrupted if a train occupies the block section C, but this partial circuit is in no wise dependent upon whether or not the control section D and the block section E are occupied. This condition, which exists before the first wheels 14 and axle 15 of the train enter the control section B, may be used in cases where the construction of the device K makes it desirable that each time a train approaches a block section the shoe 20 of the train should strike a ramp between which and a track rail a difference of potential should exist, provided the next block section, as C, is unoccupied, and regardless of whether or not the next succeeding block section, as E, is occupied. To obtain this result the ramp R may be made long enough and so located with reference to the insulating joint 3 at the entrance to the control section B that the first shoe 20 of the train will make electrical contact with said ramp before the first pair of wheels 14-14 and their axle 15 enter the control section B.

Another factor which determines the length and location of the ramps and which may be noted at this time, is that the front end of a ramp must be a greater distance from the insulating joint 3 at the entrance to the next block section than the distance between the last pair of wheels and axle of the train and the last contact shoe 20, in order that the last contact shoe 20 will have discontinued electrical contact with the ramp by the time the last pair of wheels and axle leave the control section.

When the first pair of wheels 14-14 and axle 15 of the train enter the control section B the ramp relay 8 of said control section is energized according to the following circuit: battery 12, conductors 11 and 10, relay 8, conductor 9, track rail 2, wheels 14, the axle 15, track rail 1 and conductor 13

back to the battery 12. When the relay 8 is energized its armature 30 is raised, thereby interrupting the first partial circuit hereinbefore traced which normally maintains a difference of potential between the ramp R and the track rail 1. However, under the conditions assumed the control section D is unoccupied and the armatures 30¹ and 31¹ of the relay 8¹ of the control section D are in their lower position, as shown; and since the block section E is unoccupied, the armatures 32¹ and 33¹ of its track relay 7¹ are in their upper position, as shown. Consequently, when the armature 30 of the relay 8 of the control section B is raised, a second partial circuit for maintaining a difference of potential between the ramp R and the track rail 1 is established as follows: from the ramp R, conductor 34, armature 30 of the relay 8 in its upper position, conductor 38, armature 31¹ of the relay 8¹ in its lower position, conductor 39¹, armature 33¹ of the track relay 7¹ in its upper position, conductors 40¹, 37¹ and 11¹, battery 12¹, conductor 13¹ to the track rail 1. It is noted that this last mentioned second partial circuit is interrupted if the control section D or the block section E are occupied by a train, but is not affected by the presence of a train in the block section C, and the result is that, as the wheels of the train enter the block section C and cause the track relay 7 thereof to be deenergized, this last-mentioned partial circuit will not be interrupted; but will be maintained until the last pair of wheels and axle of the train have left the control section B.

When the shoe 20 engages the ramp R it is raised and electrical contact between the contact spring 22 and the contact member 23 is broken, thereby interrupting the following normally closed circuit through the control relay 25: from the battery 26, conductor 44, contact member 23, contact spring 22, conductor 45, armature 27 of the control relay 25 in its upper position, conductors 46 and 47, control relay 25 and conductors 48 and 49 back to the battery 26. Also, as soon as the shoe 20 makes electrical contact with the ramp R and shortly before the contact spring 22 is separated from the contact member 23, current will be supplied to the control relay 25 from the ramp R according to the following circuit: from the battery 12¹, conductors 11¹, 37¹, and 40¹, armature 33¹ of the track relay 7¹ in its upper position, conductor 39¹, armature 31¹ of the ramp relay 8¹ in its lower position, conductor 38, armature 30 of the ramp relay 8 in its upper position, conductor 34, ramp R, shoe 20, conductors 50 and 48, control relay 25, conductors 47 and 51 to the frame 18 of the train, and thence through the wheels and axle to the track rail 1 and along conductor 13¹ back to the battery 12¹. In

this way, each time the shoe 20 engages a ramp the control relay 25 will be kept energized and the vehicle may proceed safely, providing a difference of potential exists 5 between that ramp and a track rail.

For the next condition to be considered, assume that the train is in the block section A and about to enter the control section B; that said train has found the track 10 unobstructed and is running without being under the dominance of the train control device K; and that there is no train in the block section C, but there is a train in the block section E. In this case the track relay 7¹ of the block section E will be deenergized by the presence of the train in said block section, as will be understood by those skilled in the art, and the armature 33¹ of said track relay will be in its lower position, 15 thereby interrupting the second partial circuit for maintaining a difference of potential between the ramp R and the track rail 1 as the train proceeds through the control section B and into the block section C. 20 The first partial circuit which normally maintains a difference of potential between the ramp R and the track rail 1, however, will not be affected by the presence of the train in the block section E, as pointed out 25 hereinbefore, so that the control relay 25 on the train will be energized if a shoe 20 of said train strikes the ramp R before the first pair of wheels and axle of the train enter the control section B; and then subsequently, when said first pair of wheels and 30 axle enter the control section B, the control relay 25 will be deenergized.

When the control relay 25 is deenergized its armature 27 drops and interrupts the 40 normally closed circuit from the battery 26 through the control relay 25 so that after the shoe 20 leaves contact with the ramp R and the contact spring 22 makes electrical contact with the contact member 23, the control relay 25 will remain deenergized. Also, 45 when the control relay 25 is deenergized, its armature 28 drops and interrupts the following normally closed circuit through the control device K: from the battery 29, conductor 52, control device K, conductor 53, armature 28 in its upper position and conductor 54 back to the battery 29. In this way, when the train occupies the block section E, the control device K will be set into 50 operation, and may operate to apply the brakes automatically or may be used to set any suitable train control apparatus of some other description into operation. The same result is produced in case the control section 55 D is occupied, as by a single locomotive or motor car, since in this case the ramp relay 8¹ of said control section D will be energized and its armature 31¹ raised to interrupt the second partial circuit for main-

taining a difference of potential between the ramp R and the contact ramp 1.

For the next condition to be considered, assume that the train is in the block section A and is about to enter the control section B, and that the block section C is occupied. 70 In this case the train before it entered the block section A would have been placed under the dominance of the control device K, since the presence of a train in the block C would have set the control apparatus K 75 into operation at the entrance to the block section A, in the same way as the presence of a train in the block section E causes the control device K to be set into operation when the train entered the block section C, 80 as hereinbefore explained. The presence of the train in the block section C requires that the train in the block section A must either stop before it enters the block section C or must proceed with great caution and at a 85 low speed under the dominance of the train control apparatus; and, consequently, to accomplish this result, no difference of potential should exist between the ramp R and the track rail 1, in order that the following 90 train will not be released from the dominance of its train control apparatus. This absence of any difference of potential between the ramp R and the track rail 1 is 95 effected by reason of the fact that the presence of a train on the block section C causes the deenergization of the track relay 7, with the result that its armature 33 drops and interrupts the first partial circuit, hereinbefore set forth, which normally maintains a 100 difference of potential between the ramp R and the track rail 1.

The modified arrangement of circuits shown in Fig. 2 is substantially the same as the arrangement of circuits in Fig. 1, except that the ramp relays 55 in Fig. 2 are arranged on a normally closed circuit, instead of on a normally open circuit as in Fig. 1. Each control section B and D is provided with a track battery 59 connected 105 across the track rails 1 and 2 and the ramp relay 55 is connected by wires 56, 57 and 58 across the track rails 1 and 2, without, however, a battery being included in said wires as is the case in Fig. 1. In this arrangement of circuits the ramp relay 55 is normally energized from the track battery 59 and when a pair of wheels and axle enter the control section B the battery 59 is shunted to deenergize the relay 55. Because of this change from a normally open 110 to a normally closed circuit, the contacts of the armatures of the ramp relay 55 are reversed, as will be clearly understood by those skilled in the art. A further difference between Fig. 2 and Fig. 1 is that the battery 64 for establishing a difference of potential between the ramp R and the track 115

rail 1 is interposed in the conductor between said ramp and the armature 60 of the ramp relay 55. In other respects, the parts and their electrical connections are the same in 5 Fig. 2 as in Fig. 1.

Without entering into a detail description of the operation of the modified arrangement of circuits shown in Fig. 2, the first partial circuit for normally maintaining a difference of potential between the ramp R and the track rail 1 is traced as follows: from the ramp R, conductor 65, battery 64, conductor 66, armature 60 of the ramp 55 in its upper position, conductor 67, 10 armature 62 of the track relay 7 in its upper position, conductors 68, 69 and 57 to the track rail 1. When the control section D and the block section E are not occupied and the first pair of wheels and axle of the 15 train enter the control section B, the second partial circuit for maintaining a difference of potential between the ramp R and the track rail 1 is as follows: from the ramp R, conductor 65, battery 64, conductor 66, armature 60 of the ramp relay 55 in its lower position, conductor 70, armature 61¹ of the ramp relay 55¹ in its upper position, conductor 71¹, armature 63¹ of the track relay 7¹ in its upper position, conductors 72¹, 69¹ 20 and 57¹ to the track rail 1. The operation of the modified arrangement of circuits shown in Fig. 2 for different conditions will be obvious by comparison with the similar operation of the arrangement of circuits 25 shown in Fig. 1; and a detail description 30 will not be given.

Although I have particularly described the construction of one physical embodiment of my invention, and explained the 40 operation and principle thereof; nevertheless, I desire to have it understood that the form selected is merely illustrative, but does not exhaust the possible physical embodiment of the idea of means underlying my 45 invention.

What I claim as new and desire to secure by Letters Patent of the United States, is:

1. In an automatic train control system, in combination: a railway trackway adapted for moving vehicles and comprising electrically isolated block sections, a comparatively short control section at the entrance to each of said block sections and electrically isolated therefrom, an insulated ramp positioned near the entrance to each of said block sections, a ramp relay associated with each control section and controlled by the presence of a train on the corresponding control section, a source of electric current 50 and a track relay associated with each block section and constituting a normally closed track circuit, and a partial circuit controlled by the corresponding ramp relay and the track relay of the next succeeding block 55 section for creating a difference of potential between each of said ramps and a track rail.
2. In an automatic train control system, in combination: a railway trackway adapted for moving vehicles and comprising electrically isolated block sections, a comparatively short control section at the entrance to each of said block sections and electrically isolated therefrom, an insulated ramp positioned near the entrance to each of said block sections, a ramp relay associated with each control section and controlled by the presence of a train on the corresponding control section, a source of electric current 60 and a track relay associated with each block section and constituting a normally closed track circuit, a partial circuit controlled by the corresponding ramp relay and the track relay of the next succeeding block section for creating a difference of potential between each of said ramps and a track rail, 65 and another partial circuit for creating a difference of potential between said ramp and a track rail which is controlled by the ramp relay of the next succeeding control section and the track relay of the second succeeding block section.
3. In an automatic train control system, in combination: a railway trackway adapted for moving vehicles and comprising electrically isolated block sections, a comparatively short control section at the entrance to each of said block sections and electrically isolated therefrom, an insulated ramp positioned near the entrance to each of said block sections, a source of electric current and a track relay for each block section constituting a normally closed track circuit, each of 70 said track relays having a pair of co-operating contacts which are closed when said relay is energized, a relay associated with each ramp, a circuit for each ramp relay connected across the track rails of the corresponding control section and including a source of electric current, said ramp relays 75 being energized when the wheels of a train are on said control sections, circuit controllers operated by said ramp relays and two partial circuits for each ramp arranged in multiple and in series with a source of current, said partial circuits creating a difference of potential between said ramp and a track rail, one of said partial circuits being closed when the ramp relay of the corresponding ramp is deenergized and the track 80 relay of the next succeeding block section is energized, and the other partial circuit being closed when said ramp relay is energized and the track relay of the second succeeding block section is energized.
4. In an automatic train control system, in combination: a railway trackway adapted for moving vehicles and comprising electrici- 85

- cally isolated block sections, a comparatively short control section at the entrance to each of said block sections and electrically isolated therefrom, an insulated ramp 5 positioned near the entrance to each of said block sections, circuit controlling devices associated with each control section, a circuit controlling device associated with each block section, a partial circuit associated 10 with each ramp for creating a difference of potential between that ramp and a track rail; said partial circuit being controlled by the circuit controlling devices of the corresponding control section and the block 15 section next ahead and being interrupted when either said control section or said block section is occupied by a train, and another partial circuit associated with each ramp and in multiple with said first-men- 20 tioned partial circuit for creating a difference of potential between said ramp and a track rail, said second partial circuit being controlled by the circuit controlling devices of the control section next ahead and the 25 second block section ahead and being interrupted when either said control section ahead or said second block section ahead is occupied.
5. In an automatic train control system, 30 in combination: a track divided into track circuit block sections and comparatively short control sections one at the entrance to each block section; an impulse device associated with each block section; control circuits for each impulse device governed respectively by the track circuit of the corresponding block section and the track circuit of the block section next in advance; and means associated with each control section 35 40 and responsive to the presence of a train thereon for selectively controlling the connection between the corresponding impulse device and its controlling circuits.
6. In an automatic train control system, 45 in combination: a track divided into track circuit block sections and comparatively short control sections one at the entrance to each block section; an impulse device associated with each block section; a relay 50 55 and a source of current connected to each control section and constituting means for detecting the presence of a train on that control section; and means associated with each impulse device and controlled by the relay of the corresponding control section for governing said impulse device successively in accordance with traffic conditions in the corresponding block section and in the next block section in advance.
- 60 7. In an automatic train control system, in combination: a track divided into track circuit block sections and comparatively short control sections, one at the entrance to each block section; an impulse device 65 associated with each block section; a relay and a source of current connected to each control section and constituting means for detecting the presence of a train thereon; a controlling circuit for each impulse device governed by the track circuit of the corresponding block section; a second controlling circuit for each impulse device governed by the relay of the control section next in advance and also by the track circuit of the block section next in advance; 70 and means associated with each impulse device and controlled by the relay of the corresponding control section for connecting the first control circuit to that impulse device prior to the entrance of a train into 75 said corresponding control section and for connecting the second control circuit to that impulse device after a train enters said corresponding control section and so long as any part of such train remains on that control section.
8. In an automatic train control system, in combination: a track divided into track circuit block sections; a comparatively short control section at the entrance to each block 80 section; a relay and a source of current connected to each control section and constituting means for detecting the presence of a train thereon; an insulated ramp located at the entrance to each block section; a partial 85 circuit for normally energizing each ramp controlled by the track circuit of the corresponding block section; a second partial circuit associated with each ramp and controlled by the track circuit of the block section next in advance; and means controlled 90 by the relay of each control section for disconnecting the corresponding ramp from its first partial circuit and connecting it to its second partial circuit when a train enters 95 that control section and so long as any part of such train remains on that control section.
9. In an automatic train control system, in combination: a track divided into track circuit block sections; a comparatively short control section at the entrance to each block section; a relay and a source of current connected to each control section and constituting means for detecting the presence of a train thereon; an impulse device at the entrance to each block section; and means associated with each impulse device and controlled by the relay of the corresponding control section for maintaining said impulse 100 device in a controlling condition while any part of a passing train occupies said control section in accordance with the presence or absence of another train in the next control section or the next block section in advance.
10. In an automatic train control system, in combination: a track divided into track circuit block sections; a comparatively short control section at the entrance to each block section; a ramp at the entrance to each block 105 110 115 120 125 130

section; means associated with each ramp and controlled by the corresponding control section and corresponding block section for establishing a difference of potential between said ramp and a track rail when neither said control section or said block section is occupied; other means associated with each ramp and controlled by the control section and block section next in advance for establishing a difference of potential between said ramp and a track rail when neither that control section or that block section is occupied; a vehicle adapted to travel over said track; automatic train control apparatus on the vehicle; and means on the vehicle responsive to the existence of a difference of potential between a ramp and a track rail for controlling said apparatus.

OSCAR A. ROSS.
